UNITED STATES PATENT OFFICE.

ROBERT BLADES, OF CHICAGO, ILLINOIS.

SKINNING KNIFE.

Application filed August 21, 1922. Serial No. 583,197.

To all whom it may concern:

Be it known that I, ROBERT BLADES, a citizen of the United States, and a resident of the city of Chicago, in the county of Cook and State of Illinois, have invented certain new and useful Improvements in a Skinning Knife; and I do hereby declare that the following is a full, clear, and exact description of the same, reference being had 10 to the accompanying drawings, and to the numerals of reference marked thereon, which form a part of this specification.

This invention relates to a knife such as is disclosed in my application Serial No. 15 551,926 for a skinning knife, filed April 12th, 1922.

It is an object of the present invention to provide means by which the blade in such a knife may be quickly protruded into a suitable position for honing or grinding and quickly returned to its normal position for use.

It is a further object of this invention to provide means for adjusting the position of 25 the knife within the housing whereby the wear of the knife through use and grinding may be compensated by proper adjustment of the projection of the blade from the housing.

It is further the object of this invention to provide means for preventing the fluid from leaking from the housing back toward the handle of the knife.

It is a further object of this invention to 35 provide a means whereby, when the knife is returned to using position after having been protruded for grinding, it shall be securely held in said position.

It is a further object of this invention to 40 provide more convenient means for attaching the knife to a hose.

Other and further important objects of this invention will be apparent from the disclosures in the specification and drawings.

The invention (in a preferred form) is illustrated in the drawings and hereinafter more fully described.

On the drawings:

Figure 1 is a side view of the knife.

Figure 2 is a back view of the knife.

Figure 3 is a section upon the line 3—3 of Figure 2.

Figure 4 is a section upon the line 4—4 of Figure 3.

Figure 5 is a section upon the line 5—5 of Figure 3.

Figure 6 is a section upon the line 6—6 of Figure 3.

Figure 7 is a section upon the line 7—7 on an enlarged scale, only that portion of the knife near the edge being shown.

As shown on the drawings:

The knife is supplied with a casting 10 which consists of a combined handle and 65 housing. The handle is hollow as shown at 11 for the reception of the end of a hose 12 which is provided with any suitable screw fixture. The casting is provided with screw threads 13 for the reception of this fixture, 70 and the sides of the handle are provided with holes 14 through which the fixture may be readily reached for screwing it into or removing it from the threads 13. The threads 13 are situated at the rear end of a conduit 75 15 which leads from the hose 12 to the interior of the housing surrounding the blade, as explained in the above mentioned application.

The blade is positioned within the housing by means of spacing lugs 17 and 18 which are shown in dotted lines in Figure 3. Through the blade 19 and each set of the spacing lugs 17 goes a screw 20, the head of which is seated in a countersunk recess 21 85 in the outer face of one side of the housing. In the other side of the housing is a threaded hole for the reception of the threaded end of the screw.

By tightening the screw 20, the lugs 17 90 may be made to contact with a blade 22 with any desired degree of friction. The lugs 18 at the end of the housing are not provided with such grooves as they are too near the back of the housing to enable the 95 motion which must accompany the above described tightening to occur. The blade is provided with slots 23 through which the screws 20 pass. These slots are not parallel to one another but make an angle so that 100 the motion of the blade in sliding over the screws is not a straight line motion but a sort of swinging motion.

Extending rearwardly from the blade is a shank 24 at the end of which is a hole for 105 a screw 25. This screw enters a post 26 to do which it passes through a slot 27 in the sleeve 28 which lines the oblique hole in the casting 10 provided for the post 26. The outer surface of the casting is provided with 110

a dove-tailed groove 29 in which is slidably mounted a traveller 30. In order to provide sufficient depth for this groove so that it will properly accommodate the traveller, 5 shoulders 31 are provided upon the casting 10 but even with the extra thickness afforded by these shoulders the bottom of the groove 29 is separated from the sleeve 28 by a very thin wall 32 which is a part of the 10 casting 10. The post 26 has its upper end threaded as shown at 33 and an upper portion 34 is screwed onto this end. This portion is provided with a slot 35 in its upper end by means of which it may be rotated 15 with a screw driver or similar tool to adjust the position of the post 26 and so of the blade 22. The upper portion of 34 of the post is provided with a groove 36 which receives the inner end of a screw 37 which is threaded into the traveller 30. The upper 20 side of the groove 36 is bordered by a collar 38 which affords a shoulder against which the lining 39 of the upper part of the sleeve 28 bears. The sleeve 28 fits tightly in the 25 hole provided in the casting 10 and the lining 39 fits tightly in the sleeve 28. Accidental movement of either the sleeve or the lining is thus prevented by friction and leakage from the passage 15 into the hole 30 containing the post 26 is prevented by the tight fit of the sleeve. The sleeve 28 and the thin wall 32 of the casting 10 are provided with registering slots 40 through which the screw 37 extends and in which 35 the screw travels during the movement of the traveller 30.

The lower end of the sleeve 28 opens into an arched narrow opening 41 which contains the shank 24 and the arrangements for moving it. To protect the space 41 from the fluid in the passage 15 and the housing surrounding the blade, a packing is provided. For this purpose oblique holes are made in the casting 10 and lined with bushings 42. The bushings may, if desired, extend below the lower surface of the casting as shown in Figure 6 and also in Figure 1. Preferably, the bushings 42 are of some flexible material such as rubber and are reinforced by other flexible material within them as is shown at 43. The blade 22 where it joins the shank 24 passes between the bushings 42 and compresses them and the reinforcement 43 thus making a tight joint 45 between the bushings and the blade so that leakage is prevented, and chattering and movement of the blade is also prevented.

In the operation of the device, when the user desires to connect the hose 12 with the 60 instrument, the end of the hose with its fixture is inserted into the hollow 11. This brings the knurled surface 45 opposite the holes 14 so that the operator may use his thumb and forefinger, one upon each side 65 of the handle, to turn the fixture and screw

it into the threads 13. Suitable stop cock provided at any point in the length of the hose 12 being opened, fluid passes through the passage 15 and into the interior of the housing from whence it emerges around the 70 edge of the blade through the openings 46 as explained in the above mentioned application.

When the knife has become dull it is not necessary to remove the blade for grinding, 75 but the same may be projected from the housing a sufficient distance to enable it to be ground by thrusting the traveller 30 downward in Figure 1. This causes the screw 37 to move downward and so moves the 80 post 26 downward thus moving the shank 24. The blade 22 is guided in its movement by the slots 23 and by the contact of the post 26 with the sleeve 28. The angles between these three guides are so designed 85 that the blade is projected with a swinging motion and each part of the curved edge comes far enough out of the housing to enable the whole edge to be ground. As the 90 blade wears away through use and repeated grinding, it is necessary that the retracted portion of it be adjusted so that the edge will project from the housing the correct amount at all times. This adjustment is effected by turning the upper part 34 of the 95 post 26 by means of the screw driver slot 35. As illustrated in Figure 4, this adjustment is at the extreme position which it would occupy with a new or full-sized blade.

Rotating the part 34 causes the threaded end 33 of the post 26 to travel outwardly in the socket in the lower end of the part 34. The collar 38 and the tight lining 39 prevent motion of the part 34 upward. Consequently, the post 26 is obliged to travel 105 downward and so moves the shank 24 downward. This moves the post and blade relative to the traveller 30 because this traveller is held still by the engagement of the screw 37 in the groove 36. Thus, although the 110 position of the blade is adjusted, the position of the head of the screw 37 by which the workman would move the traveller remains unaltered.

It is unnecessary to loosen the screws 20 115 before projecting the traveller downward since if they are properly adjusted, they will permit the blade to slide freely enough for such intentional projection of it. If, however, the screws through accident or lack of 120 skill or intentionally have been tightened so much that the traveller 30 cannot be moved, it requires only a moment to loosen them when it is desired to project the blade for 125 sharpening. When the screws 20 are at the right degree of tightness, the friction of the blade against the lugs 17 and of the post 26 against the sleeve 28 and of the traveller 30 against the sides of the groove 29 will be sufficient to hold the blade in retracted position.

tion. This friction is sufficient for this purpose because in the use of the knife, the pressure of the work against the edge is in the direction to force the blade toward the 5 illustrated position and not to cause it to project. Moreover, in grasping the handle, the workman's fingers come against the lower end of the traveller 30 and prevent its accidental movement downward. If 10 however, there should be any likelihood of the blade being accidentally projected through its use for unusual work or in the hands of an unskilled man, the blade could be certainly retained in retracted position 15 by tightening the screws 21.

I am aware that numerous details of construction may be varied through a wide range without departing from the principles of this invention, and I therefore do not 20 purpose limiting the patent granted otherwise than necessitated by the prior art.

I claim as my invention:

1. In a knife, a casting comprising a handle and a blade housing, a conduit through 25 said handle to said housing, a supply pipe for said knife, a threaded fixture connecting said pipe with said conduit, the handle being provided with orifices whereby the fixture is readily reached for screwing or unscrewing.

2. In a device of the class described, a blade, a housing surrounding said blade, means for conducting fluid to the interior of said housing, a blade adjusting mechanism, and fluid-tight means separating said 35 housing from said blade adjusting mechanism.

3. In a device of the class described, a blade, a handle for the blade, a traveller 40 slidably mounted on the handle for altering the position of the blade relatively to the handle, and an adjustable connection between the traveller and blade.

4. In a device of the class described, a blade, a handle, a housing connected to handle 45 and surrounding said blade, said blade having slots and said housing having screws passing through said slots, means for moving said blade relative to said handle, said slots being non-parallel whereby said moving means will protrude a certain portion

of the blade in a different direction from another portion.

5. In combination, a hollow housing, a hollow handle, a cutting instrument having its blade portion within the housing, said 55 handle having a recess, means in the recess for moving the blade, a connection between said means and said blade, and a packing contacting said connection and located between said recess and said housing. 60

6. In a skinning knife, a housing, a blade within said housing, the edge of said blade projecting beyond said housing, and manually operated means for causing said edge to project further from said housing and for 65 retracting said blade after such additional projection.

7. In a cutting instrument, a blade, a casting including a housing surrounding said blade, said casting having a hole oblique to 70 the length of the blade, a member slidably mounted in said hole, a connection between said blade and said slidably member, an actuating means slidably mounted on the exterior of said casting, and an adjustable 75 connection between said last-mentioned means and the member.

8. In combination, a blade, a handle for said blade, a shank extending from said blade into said handle, said handle having a 80 hole, a post mounted in the lower part of said hole, a connection between said shank and said post, a member rotatably mounted in the upper part of said hole, an obstacle in the wall of said hole and preventing upward movement of said member, a screw connection between said post and said member, and means actuated from outside of the handle for moving said member and post axially of said hole, said member having 85 means accessible from outside the handle by which it may be rotated.

In testimony whereof I have hereunto subscribed my name in the presence of two subscribing witnesses.

ROBERT BLADES.
